PATTERN DRAFTING INSTRUMENT

Fructuosa Casso, San Antonio, Tex.

Application November 21, 1935, Serial No. 50,937

1 Claim. (Cl. 33—11)

This invention appertains to new and useful improvements in instruments whereby patterns can be laid out in an easy and convenient as well as economical manner.

An important object of the invention is to provide an instrument of this character which will permit every line of a pattern to be laid out without resorting to other instruments.

During the course of the following specification other important objects and advantages of the invention will become apparent.

In the drawings:

Figure 1 represents an elevational view of one side of the instrument.

Figure 2 is an edge elevational view of the instrument.

Figure 3 is an elevational view of the opposite side of the instrument from that shown in Figure 1.

In the drawings wherein like numerals designate like parts, it can be seen that the instrument consists of an elongated plate 5 having the longitudinally extending straight edge 6 and the right angularly disposed straight edge 7 on the foot portion 8.

Extending inwardly from the top of the foot portion 8 is the curved edge 9 having the graduations 10 adjacent thereto and from the peaked point 11 another curved edge 12 extends to the peak point 13 of the gradual curved edge portion 14 of the shoulder portion 15 of the instrument. This edge portion 14 is marked with characters 16.

The straight edges 6 and 7 are laid off in inches, in third inches, halves and quarter inches.

The instrument can be used in laying off various patterns for dresses and other garments with

considerable ease, the various curved formations being utilized in the manner of a drafting instrument to mark off the several curved outlines of the pattern, such as the neck, armholes, etc., the several scales being used to obtain the measurement of the different parts of the body of the person for whom the garment is to be made.

While the foregoing specification sets forth the invention in specific terms, it is to be understood that numerous changes in the shape, size and materials may be resorted to without departing from the spirit or scope of the invention as claimed hereinafter.

Having thus described the invention, what is claimed as new is:

A pattern drafting instrument comprising an elongated plate provided with a laterally extending foot portion at one end thereof, said elongated plate being provided with a longitudinally extending straight edge, said foot portion being provided with a straight edge at right angles to the first mentioned straight edge, said plate being provided with a relatively broad shoulder portion having a gradually reduced curved edge at the opposite end of the plate from the foot portion, and a plurality of semi-circular cut-out portions defining a series of individual curved edges extending inwardly from the top portion of the foot, said semi-circular cut-out portions being curved to correspond to the different body formations of a dress pattern, the end of said foot portion being rounded and said shoulder and foot portions having a sharply defined point of termination with the respective adjacent semi-circular cut out portions.
